UNITED STATES PATENT OFFICE

159,133

BOTTLE OR THE LIKE

Miguel Bienvenido Sorribes, Barcelona, Spain

Application January 14, 1948, Serial No. 143,735

Term of patent 7 years

(Cl. D58—6)

To all whom it may concern:

Be it known that I, Miguel Bienvenido Sorribes, a citizen of Spain, residing at Barcelona, Province of Barcelona, city of Barcelona, 88 Alava Street, have invented a new, original, and ornamental Design for a Bottle or the like, of which the following is a specification, reference being had to the accompanying drawing, forming a part thereof.

I claim:

The ornamental design for a bottle or the like, as shown.

MIGUEL BIENVENIDO SORRIBES.
